UNITED STATES PATENT OFFICE.

EDWIN D. McCACKEN, OF PATERSON, NEW JERSEY.

UNDERGROUND ELECTRIC CONDUCTOR.

SPECIFICATION forming part of Letters Patent No. 351,193, dated October 19, 1886.

Application filed May 17, 1884. Renewed August 19, 1886. Serial No. 211,263. (No model.)

To all whom it may concern:

Be it known that I, EDWIN D. McCACKEN, of the city of Paterson, in the county of Passaic and State of New Jersey, have invented a new and useful Improvement in Underground Electric Conductors, of which the following is a specification.

My invention relates to electric conductors which are laid in tubes or conduits under ground, the tube or conduit being composed of sections joined by couplings, and a large number of conductors being inclosed therein.

My invention is more particularly intended for compound conductors, each consisting of a primary conductor and a secondary conductor for induced currents, but may be employed in laying simple conductors.

The invention consists in the combination, with tube-sections composed of spirally-wound and superposed strips of pure vegetable paper, the sections being laid with separated ends and connected by coupling-sleeves, of conductor-sections arranged in each tube-section, and each having an insulation of spirally-wound strips of pure vegetable paper, the conductor-sections in adjacent tube-sections being joined between the ends of the tube-sections, and a filling of insulating material within the tube-sections and coupling-sleeve, in which the conductors are embedded. By such a combination a large number of conductors may be laid in a tube of comparatively small size, and are effectively insulated by the paper coverings, the insulating material in which they are embedded, and the spirally-wound paper of which the tube-sections are composed. The filling of insulating material is put in while in a fluid or plastic state, and penetrates and preserves the paper coverings of the conductors and the paper of which the tube-sections are composed.

In the accompanying drawings, Figure 1 represents a longitudinal section of portions of two adjacent and joined tube-sections, with their contained and joined conductors. Fig. 2 is a longitudinal section of a tube-section and its contained conductor-sections suspended in position for pouring in the resin or other substance employed, the portion of the tube and conductors between the ends being broken away; and Fig. 3 represents a piece of a conductor which I prefer to use, showing the

manner of applying the insulation and secondary or induction conductor.

Similar letters of reference designate corresponding parts in all the figures.

A designates tube-sections, which may be produced in any suitable lengths desired. These tube-sections are each made of strips of vegetable paper, which are spirally wound and superposed one on another, care being taken to break joints, until the desired thickness is obtained. These strips are wound spirally under strong tension in a lathe or analogous machine, and an adhesive substance is employed in order that the superposed layers shall adhere and form a strong, solid, and homogeneous tube. The adhesive substance employed may be a solution of shellac or any suitable alkaline solution. After the tube-sections are thus produced they are coated inside and outside with bitumen, asphalt, pitch, tar, or any other suitable preservative compound, and are then completed for further use.

B designates a coupling-sleeve, which is of a size to slip on the exterior of the tube-sections, and which is or may be made in the same way by spirally winding strips of vegetable paper. These coupling-sleeves may be coated externally and internally in the same manner as the tube-sections.

C designates the conductor-sections, which may be iron or copper wires, and which are insulated separately.

When a large number of conductors are to be laid in a tube or conduit, they should be severally provided with secondary or induction conductors for the induced current produced by the passage of a primary current through the main conductor. The conductor which I prefer to use is the one shown and described in my Letters Patent No. 304,540, dated September 2, 1884; but I may employ simple conductors insulated by spirally-wound strips of vegetable paper. A piece of such a compound conductor is shown in Fig. 3. To the primary conductor *a*, I apply one or more spirally-wound strips of vegetable paper. I have here shown two strips, *b* and *b'*. These are applied with any suitable adhesive substance—such, for example, as a solution of shellac or an alkaline solution—and so as to break joints one with another. I then wind on spirally a third strip, *b''*, of similar paper, and with and

inside this I wind on spirally a fine wire or ribbon of metal, *c*, which forms the secondary or induction conductor. Outside the strip *b*² is applied another strip, *b*³, and, if desired, a 5 second strip, *b*⁴, of similar paper. By this means the primary conductor *a* is effectively insulated, and the secondary conductor *c* is insulated both from the primary conductor and externally. The compound conductors thus 10 produced have the insulation as long as the tube-sections *A*, and the uncovered ends of the conductors will project considerably beyond the ends of the tube-section when placed therein. The conductor-sections thus 15 produced should be straight, and are laid within a tube-section *A*, and the whole is then placed in an upright position, as shown in Fig. 2, and suspended.

In order to hold the conductor-sections out 20 of contact with each other, I apply templets or perforated plates *D* to opposite ends of the tube-section, and the bare ends of the conductor-sections are received through suitably-arranged perforations in these plates, whereby 25 they are held out of contact with each other and out of contact with the tube *A*. I then fill the tube-section with melted resin, asphalt, or other suitable substance or compound through a funnel, *E*, at the top, and when this 30 has set the conductors are embedded out of contact with each other in a solid mass of resin, *g*, or other substance which will contribute to the insulation of the conductors, and will penetrate and preserve the paper of which 35 the covering for the conductors and the tube-sections are composed.

In laying the tube-sections and their contained conductor-sections, they are laid at some distance apart, and the primary conductors which project from their adjacent ends are joined, as also are the secondary conductors. The joined ends of the primary and secondary conductors are then properly insulated, and the several conductors are bent or 45 placed out of contact. Of course the joined ends of the conductors require more room than would be afforded by the internal area of the tube-sections *A*; but the room afforded in the coupling-sleeve *B* is ample to accommodate 50 them. When the conductors are thus properly joined and isolated, a coupling-sleeve, *B*, is slipped on, so as to cover the space between the tube-sections and lap on each. The ends of this coupling-sleeve are then luted with 55 clay, (the ends may have a rabbet, *e*, for that purpose,) and melted paraffine is poured in through a hole, *c*, in the top of the sleeve to fill the whole interior thereof between the adjacent ends of the tube-sections, and thus the 60 joined conductors are embedded in a mass, *f*, of paraffine, which remains soft. Other sub-

stance than paraffine may be used; but it should be of such a nature that it will remain soft, as the removal of any one section and its contained conductors is thus greatly facilitated. 65

If it is desired to remove a tube-section, the sleeve *B* is slipped away from the joint, and the conductors are dug out from the soft paraffine and disconnected. The tube-section and its contained conductor-sections may thus be 70 removed without disturbing other sections.

I am aware that it is not new to make tubes by spirally winding strips of paper and to then cut such tubes into proper length to form the bodies of cylindric boxes; and I am also aware 75 that it is not new to lay a number of simple primary conductors by embedding sections of the conductors in tube-sections composed of wood, the tube-sections being laid with separated ends and united by a sleeve, and the 80 ends of conductor-sections in adjacent tube-sections being joined between the ends of the tube-sections and embedded in insulating material. I do not desire to claim the means of laying and protecting conductors above de- 85 scribed as of my invention, nor do I desire to cover, broadly, tubes made of spirally-wound and superposed strips of paper. When conductors have an insulation composed of spirally-wound strips of vegetable paper and are 90 embedded in insulating material within a tube composed of the same material, the insulating material penetrates and preserves both the paper covering of the conductors and the paper whereof the tube is made, and both the insulating-filling and the tube combine to form 95 a very perfect insulation of the conductors. The combination of conductors so insulated 100 with a tube and filling of the kind described combine to enable me to lay a larger number of wires within a tube of given size and more perfectly insulated than any system of which I have knowledge.

What I claim as my invention, and desire to 105 secure by Letters Patent, is—

The combination, with tube-sections *A*, *A*, laid with separated ends and composed of spirally-wound and superposed strips of vegetable paper, and a coupling-sleeve, *B*, connecting them, of conductor-sections *C*, arranged in the tube-sections and each having an insulation of spirally-wound strips of pure vegetable paper, the conductor-sections being joined between the tube-sections, and a filling of insulating material within the tube-sections and 110 coupling-sleeve, and in which the conductor-sections are embedded, substantially as herein 115 described.

E. D. McCACKEN.
